UNITED STATES PATENT OFFICE.

DALE W. YAMBERT, OF TOLEDO, OHIO.

REFILLABLE FUSE.

Application filed November 19, 1919. Serial No. 339,150.

To all whom it may concern:

Be it known that I, DALE W. YAMBERT, a citizen of the United States of America, residing at Toledo, Lucas County, Ohio, have invented new and useful Refillable Fuses, of which the following is a specification.

This invention relates to that type of interrupting devices for electrical circuits involving the replacement of a fusible element or link.

This invention has utility when incorporated in enclosed refillable fuses.

Referring to the drawings:

Fig. 1 is a perspective view of a ferrule type cylindrical fuse;

Fig. 2 is a perspective view of one of the portions of the fuse of Fig. 1;

Fig. 3 is a perspective view of the member coacting with the seat in the portion or section of Fig. 2;

Fig. 4 is a fragmentary longitudinal section of the device of Fig. 1, with one of the enclosing portions but partly assembled;

Fig. 5 is a view at right angles to the showing of Fig. 4;

Fig. 6 is a view of the blank for the link;

Fig. 7 is a perspective view of the link;

Fig. 8 is a view of a knife blade type of fuse;

Fig. 9 is a perspective view of one of the seat or contact elements of the fuse of Fig. 8;

Fig. 10 is a view of the element of Fig. 9 with an additional assembling feature therewith;

Fig. 11 is a perspective view of one of the enclosing elements of the device of Fig. 8; and

Fig. 12 is a section of the end of the fuse of Fig. 8.

As a housing for this fuse structure, there is provided herein a cylindrical tubular shell 1 which may be of insulating material, as fiber, which shell near each end has an inner shoulder 2. Anchored to each end of

this shell by rivets 3 is a member 4 having on its exterior terminus a threaded portion 5 and therein a pair of opposing wedge seats 6. In the device of Fig. 4 these wedge seats 6 are opposed by a wedge member 7 having a projection 8 which may be riveted to have swivel connection with an outer cap or ferrule member 9.

These members 7 and 9 thus form a unit, the member 9 being operative for threaded engagement with the threads 5 to force the

relatively non-rotatable member 7 towards the seats 6.

The element for electrical circuit interruption is herein shown as a strap or fusible link comprising two similar longitudinally extending sections 10 normally connected by bent portions 11 and otherwise separate so that in folding over from the showing in Fig. 6 to the showing in Fig. 7, tongues 12, 13, may anchor the two strips 10 into parallel relation, the broadened intermediate portions 15 being insulated from one another with a coating of varnish 14. Accordingly, there is provided in this element for electrical circuit interruption or fusible link the broadened intermediate portions 15 insulated from each other by the insulation 14. These broadened intermediate portions 15 having connection by narrowed portions or necks 16 with the broadened terminal portions 17. These flattened terminals 17 may be opened out against the contact seats 6 and engaged by wedge 7 for a distributed or large contact surface in anchoring with the member 4 by the wedge 7 screwed thereagainst by the member 9. This means a most positive and firm gripping or anchoring of the terminal or end portions of the fusible link.

In operation, of course when the amperage becomes excessive, the heating will be greatest at the neck portions 16 and when these approach a fused or molten condition, there is rupture at these weakened necks 16.

There may be ready replacement of links without the use of any tools for all that it is necessary to do is to operate the threaded member 9 to remove the member 7, swivelled thereto, out of the member 4. Of course the withdrawal of the member 7 from the member 4 is by direct action, while the turning action of the member 9 coacting with the thread 5 effects a positive drawing-out. A link having interrupted the electrical circuit, it may be readily replaced by a new link or element.

Another feature of considerable importance is the provision of an indicator or vernier mark 18 on the member 9 to coact with the indication or ampere reading 19 on the enclosing or shell member 1. This provides a means for externally identifying just exactly what may be the ampere capacity of the links used in the shell 1. But a single link may be placed in the shell at any one time, for should the terminals of two

- links be against the contact seats 6 the wedge 7 could not enter the proper distance and the assembled fuse would be of abnormal length. The link has its capacity determined by its thickness and such terminal thicknesses may be made standard for different amperage ratings. Accordingly, since different thicknesses of links will permit member 9 to be threaded on to the member 4 to a greater or less degree, a definite and positive indication of the ampere capacity of the link within will be made by the indicator mark 18 pointing to the ampere reading 19.
15. In adapting the device of this disclosure from the ferrule type of fuse of Fig. 1 to the knife blade type of fuse of Fig. 8, the wedge 7 is provided with a recess 20 in which may be welded or positively anchored a slotted member 21 over which a washer 22 may be slipped and welded or positively anchored to wedge 7. Knife blade 23 may be inserted in the slot of member 21 and welded or otherwise positively anchored in place. When so assembled as a unit of the device, the knife blade 23 may be thrust through the end of the member 9 as permitted by the wings 24, (Fig. 11). When this assembly is effected, these wings 24 may be pressed down into the plane of the end of the member 9, and the assembly for operation as well as for replacement of links occurs as with the ferrule type of fuse. Any fumes or gases from blowing of the fuse or link are sealed in the enclosed device for the member 9 is snugly against the swivel head 8 or the washer 22 is abutting the member 9 to seal the opening about the closed wings 24.
- The apparatus is of few parts, simple in construction, and may be manipulated at all times by the hands of the operator. It has exceptionally large link contacts reducing the tendency to heat during operation. It possesses the feature of indicating from without the capacity of the link within. It cannot be assembled with more than one link within, which guarantees that it cannot be over-fused. It is substantial in construction, conforming to rigid requirements of safety, as well as possessing great advantages for the operator.
- What is claimed and it is desired to secure by Letters Patent is:
1. A fuse having an enclosure, an element for electrical circuit interruption in said enclosure, and anchoring means having a scale disclosing indication in coaction with the enclosure, said means being for the purpose of disclosing the identity of the element for fuse operation.
  2. A fuse structure embodying a ribbon element for electric circuit interruption, and clamp mounting means for the element embodying a bushing having a way there-through providing an inwardly facing seat
  3. in a plane against which a terminal of the ribbon element may rest, a plug for entering said bushing and provided with a seat in a plane parallel to the plane of the bushing seat for engaging the opposite side of the element as against the bushing seat, and means having swivel connection with the plug for effecting relative travel between the plug and bushing at an angle to the plane of the seats for effecting clamping of the element therebetween.
  4. A fuse structure embodying a ribbon element for electric circuit interruption, an insulation shell, and clamp mounting means for the element in said shell embodying a bushing having a way therethrough providing an inwardly facing seat in a plane against which a terminal of the ribbon element may rest, a plug for entering said bushing and provided with a seat in a plane parallel to the plane of the bushing seat for engaging the opposite side of the element as against the bushing seat, and means having swivel connection with the plug for effecting relative travel between the plug and bushing at an angle to the plane of the seats for effecting clamping of the element therebetween.
  5. A fuse structure embodying a ribbon element for electric circuit interruption, an insulation shell, and clamp mounting means for the element in said shell embodying bushings, one fixed in each end of the shell, each bushing having a way therethrough providing a seat in a plane against which a terminal of the ribbon element may rest, plugs, one for entering each of said bushings, each plug being provided with a seat in a plane parallel to the opposing bushing seat for engaging the opposite side of the element, the extension of the planes of the seats at one end of the shell intersecting in the shell the extension of the planes of the seats at the other end of the shell, and means having swivel connection with the plugs for effecting relative travel between each plug and bushing independently of relative rotation therebetween.
  6. A fuse structure embodying a ribbon

- element for electric circuit interruption, an insulation shell, and clamp mounting means for the element in said shell embodying bushings, one fixed in each end of the shell, 5 each bushing having a way therethrough providing a seat in a plane against which a terminal of the ribbon element may rest, plugs, one for entering each of said bushings, each plug being provided with a seat 10 in a plane parallel to the opposing bushing seat for engaging the opposite side of the element, there being threaded means at each end of the shell, and a threaded actuator rotatably coacting with each of the threaded 15 means and having swivel connection with the plugs for shifting a plug.
7. A housing for a fuse element for electric current interruption, said housing embodying a first member, a second member
- movable relatively thereto into a plurality 20 of clamping positions for a fuse element therebetween, there being means for indicating the positions of the clamping of the element for disclosing the relative spacing between the members whereby there is disclosed exterior of this housing the current 25 carrying capacity of the fuse element as mounted therein.
8. A housing for a fuse element for electric current interruption, said housing embodying a first member, a second member 30 movable relatively thereto into a plurality of clamping positions for a fuse element therebetween, and means having swivel connection with the second member and rotatable as to the members and element.

In witness whereof I affix my signature.
DALE W. YAMBERT.
